(57) **CLAIM**

The ornamental design for a light module, as shown and described.

DESCRIPTION

FIG. 1 is a front perspective view of a light module showing my new design;

FIG. 2 is a front elevational view thereof;

FIG. 3 is a rear elevational view thereof;

FIG. 4 is a right side view of my new design, the left side elevational view being identical but rotated 180°; and,

FIG. 5 is a top plan view of my new design, the bottom view being a mirror image thereof.
